DESIGN FOR A BUCKLE

Herbert G. Whitehouse, Newark, N. J.

Application February 27, 1935, Serial No. 55,640

Term of patent 3½ years

To all whom it may concern:

Be it known that I, Herbert G. Whitehouse, a citizen of the United States, residing in Newark, in the county of Essex and State of New Jersey, have invented a new, original, and ornamental Design for a Buckle, of which the following is a specification, reference being had to the accompanying drawing, forming part thereof.

I claim:

The ornamental design for a buckle as shown, and described.

HERBERT G. WHITEHOUSE.
